(57) **CLAIM**

The ornamental design for a modular jack housing, as shown and described.

DESCRIPTION

FIG. 1 is a bottom and right front perspective view of a modular jack housing, showing our new design.

FIG. 2 is a front elevational view thereof.

FIG. 3 is a rear elevational view thereof.

FIG. 4 is a right side elevational view thereof, the left side elevational view being a mirror image of the right side elevational view.

FIG. 5 is a top plan view thereof.

FIG. 6 is a bottom plan view thereof.

FIG. 7 is a sectional view taken along line 7—7 of FIG. 2 with the internal parts omitted; and,

FIG. 8 is a sectional view taken along line 8—8 of FIG. 2 with the internal parts omitted.

1 Claim, 6 Drawing Sheets

FIG. 1

FIG. 2
